CENTER SILL FILLER ASSEMBLY

Cyrus Hankins and Orville Ingram,
Washington, D. C.

Application November 5, 1946, Serial No. 707,832

7 Claims. (Cl. 213—57)

1

Our invention relates to a new and improved filler assembly for the center sills of railway cars. The center sill filler now approved by the American Association of Railroads is objectionable in that it is made as a one piece casting. It is, therefore, necessary to machine the sides of such a casting so that it will be of a width not exceeding the usual fitting tolerances. Moreover, after the casting is made, it is necessary to drill holes in its side walls matching those already in the center sills to permit the casting to be easily riveted to the sills. It is not feasible to form the rivet holes during the casting operation of the filler because of the possibility of shifting cores. The extra cost of these operations has resulted in many attempts to design a satisfactory welded center sill filler to replace the costly one piece casting now acceptable. Due to the limited working space between the center sills of the car and the consequent inaccessibility of some parts of the structure requiring welding, all attempts to provide a satisfactory welded center sill filler have been unsuccessful.

The primary object of the present invention is to provide a welded filler block assembly which may be completely formed in sections with the use of suitable jigs prior to insertion between the center sills of the car.

A primary feature of the invention consists in providing a filler block assembly formed of two separate castings respectively secured to rolled sections which are adapted to be attached to the center sills of the car, the castings being secured to the rolled sections and to each other before the assembly is inserted between the center sills of the car.

Another feature of the invention consists in providing the castings of the filler assembly with curved portions which, when the castings are suitably secured together, mutually cooperate to provide a king pin receiving opening.

A further feature of the invention consists in respectively providing a pair of oppositely disposed members with rigid castings, each of which has an upright portion which is welded at one edge to one of said members and is formed with a curved portion adjacent the other edge, the castings being rigidly connected so that the curved portions thereof will cooperate to mutually form a king pin receiving opening.

A still further feature of the invention consists in providing a filler block assembly having castings respectively welded to oppositely arranged members, the castings being welded together in a direction which is substantially parallel with

2

the longitudinal axis of the car and the members being adapted to be secured to the center sills after the castings are secured to each other.

A still further feature of the invention consists in providing a combined center sill and rear draft gear stop assembly involving a pair of castings respectively rigid with a pair of oppositely disposed members, rear draft gear stops being welded to the forward ends of said members and reinforced by substantially horizontally arranged ribs welded to the members, the members being adapted to be respectively secured to the center sills of the car after the castings have been welded to each other.

Other and more specific features of the invention, residing in advantageous forms, combinations and relations of parts, will hereinafter appear and be pointed out in the appended claims.

In the drawings,

20 Figure 1 is a horizontal sectional view of the center sills of a railway car showing the filler block assembly partly in section and partly in plan.

Figure 2 is a sectional view taken on line 2—2 of Figure 3.

Figure 3 is an enlarged transverse sectional view taken on line 3—3 of Figure 1.

Figure 4 is a plan view of one of the castings of the center filler.

Figure 5 is a side view of the casting shown in Figure 4.

Figure 6 is an end view of the casting shown in Figure 4.

Figure 7 is an enlarged detail view taken on line 7—7 of Figure 1.

Figure 8 is a detail view taken on line 8—8 of Figure 3.

Referring more particularly to the drawings, 1 indicates the center sills of the car, each of which is preferably of Z section having a web 2 and oppositely projecting top and bottom flanges 3 and 4. The free edges of the top flanges of the sills are conveniently disposed contiguously to each other so that they may be welded securely together as indicated at 5.

The filler block assembly may advantageously employ a pair of inwardly opening rolled members 6 of channel section. These members may be twelve inch standard channel sections each having top and bottom flanges 7 and 8 respectively connected by a web 9. Secured to each of the members 6, preferably by welding, is a casting 10 formed with a web 11 and a base plate portion 12. The upright web of each casting is

welded, as indicated at 13, to the web 9 as well

as to the top flange 7 of the channel with which the casting is associated. The free end of the web of each casting is formed with a circular portion 14 which extends on opposite sides of the web and its axis of curvature is substantially vertical.

Integrally formed with one edge of each curved portion 14 is a rigidifying rib 15 adapted to extend substantially longitudinally of the car. The outer face of the rib of each casting preferably terminates in line with the free edge of the other part of the curved portion and they both are advantageously in line with the axis of curvature. By this construction, neither of the castings is right nor left. At its upper end, the rigidifying rib 15 merges into an inclined top flange 16 of the casting and at its lower end it is integrally formed with the base 12.

The curved portions 14 of the castings are preferably so formed that, when the castings are secured to each other, they form a substantially vertical opening for receiving a king pin (not shown) which affords a pivotal connection between the body of the railroad car and the car truck. The castings may be advantageously connected by being welded, as indicated at 17, which may extend continuously along the inner face of the rigidifying rib 14 of each casting where it abuts the curved portion of the other casting. In addition, the castings may be welded, as indicated at 18, along the top of the base plates 12 where they abut the rigidifying ribs of the castings. The castings may also be welded, as indicated at 19, along the under sides of the base portions of the castings without the necessity of grinding because the welded area of the bases is sufficiently spaced above the lowest portions thereof.

Before the castings are secured together and the assembly thereafter inserted between the center sills, the castings are separately secured to their cooperating channel sections. The two parts of the center filler may, therefore, be easily and quickly welded to the members which are subsequently attached to the center sill. Prior to welding a casting to its associated member, a rear draft gear stop 20 may be conveniently secured to the forward edge of each member by welding 21, and a plurality of ribs 22 may also be conveniently welded, as indicated at 23, to the inner face of the member to reinforce or rigidify the portions of the back stop 20 intermediate the top and bottom flanges of the member 6.

In addition to welding the web 11 of the casting to its member, as indicated at 13, the upper edge of the top flange 16 may also be welded, as shown at 24, to the top flange 7 of the member and the base plate 12 may be welded, as at 25, to the bottom flange 8. The base portion of each casting may be also secured to its associated member by a pair of rivets 26 which pass through lugs or ears 27 of the base plate and the outer portions of the bottom flange 8 of member 6, it being seen that the ears or lugs rest upon the top of that flange. To prevent the reinforcing ribs 22 of the back stop 20 from interfering with either the driving or bucking of the rivets 26, each of the ribs 22 is cut away, as indicated at 28, and continues rearwardly substantially reduced in width to the web 11 of the adjacent casting.

Filler strips 29 are preferably tack welded at their opposite ends, as indicated at 30 to the top flanges 7 of the channels 6 for engaging the un-

der side of the top flanges 3 of the center sill so as to vertically position the assembly correctly within the sills. A rear tie plate 31 of conventional construction may also be tack welded to the top flange 7 of one of the members 6. After the castings are separately welded to their channels 6 they are brought together into contiguous relation and welded to each other as previously described.

By assembling one-half of the center filler independently of the other, it is possible to securely weld to each channel all parts of the device connected to it. As previously indicated, the two main parts of the filler are separately assembled on jigs so that, when the two parts are welded together, they form a rigid center filler assembly of the width desired for insertion between the center sills. The necessity of compromising design or of risking the failure to weld or of other means of attachment is entirely eliminated, since the parts of the filler which would be inaccessible for welding when the filler is in position between the center sills may be easily welded to the rolled sections before the two parts of the filler are welded together and placed between the sills. Even the welding together of the two main parts of the filler is preferably accomplished before the filler is placed between the sills. Thus an extremely rigid and all-welded center filler is provided.

The webs 9 of the channels 6 and the webs 2 of the center sills are formed with aligned openings so that, after the filler is placed between the sills, rivets may be inserted in the openings for securely connecting the center filler to the center sills. The top flanges 7 of the channel 6, together with the fillers 29, may also be advantageously formed with aligned openings for registering with similar openings in the top flanges 3 of the center sill to receive additional rivets for connecting the filler to the sills.

It will, of course, be appreciated that by using conventional channel sections 6, sections of the desired length may be obtained by simple cutting. Various changes and modifications may be made in the structure illustrated and described without departing from the spirit and scope of the invention as defined in the appended claims.

What we claim is:

1. A filler block assembly for insertion between the center sills of a railway car involving a pair of rolled members, a casting rigid with each of said members, each of said castings including a web and a top flange welded to the member with which the casting is rigid, said castings also having curved portions, and means securing said castings together so that the said curved portions mutually cooperate to form a king pin receiving opening, said members being respectively adapted to be secured to said center sills.
2. A filler block assembly for insertion between the center sills of a railway car involving a pair of inwardly opening channel members respectively having upper and lower flanges and a connecting web, a longitudinally extending casting engaging the upper and lower flanges of each of said channels and having a base portion overlapping the lower flange of the channel to which the casting is secured, and weld means extending substantially longitudinally of the car respectively connecting said castings to said upper and lower flanges, said channel members being respectively adapted to be secured to said center sills of the car.
3. A filler block assembly for insertion be-

tween the center sills of a railway car involving a pair of members, a casting rigid with each of said members, each of said castings having a substantially vertical web and upper and lower flanges normal to said web welded to the member with which said casting is rigid, said castings also respectively having curved portions adapted to mutually cooperate to form a king pin receiving opening when the castings are connected together, and weld means connecting said castings, said members being respectively adapted to be secured to said center sills of the car.

4. A combined center filler and rear draft gear stop adapted to be inserted between the center sills of a railway car, involving a pair of side members each having an upper inturned flange, a casting rigid with each of said members, a rear draft gear stop positioned in front of each of said members and welded thereto, the top portions of said castings being respectively welded to said side members and being adapted to underlie the top flange thereof, portions of said castings forming a king pin receiving opening when connected together, and means rigidly connecting said castings, said members and castings being adapted to be secured as a unit to said center sills.

5. A combined center filler and rear draft gear stop adapted to be inserted between the center sills of a railway car, involving oppositely disposed members each having an upper inturned flange, a casting rigid with each of said members, a rear draft gear stop secured to the forward edge of each of said members, reinforcing ribs welded to the inner face of each of said stops and to said member to which the stop is secured, and weld means connecting said castings to the said top flanges and together, castings underlying the said top flanges of said members and being respectively adapted to be secured to said center sills.

6. A combined center filler and rear draft gear stop adapted to be inserted between the center sills of a railway car, involving a pair of side members, a casting each having an upper inturned flange secured to each of said members 45

having a substantially vertical transversely extending web, a rear draft gear stop secured to the forward end of each of said members, reinforcing ribs extending from each back stop to the web of the adjacent casting and welded to the member to which the back stop is secured, and weld means rigidly connecting said castings to said flanges and to each other, said members being respectively adapted to be secured to said center sills.

7. A combined center filler and rear draft gear stop adapted to be inserted between the center sills of a railway car, involving a pair of channel members respectively having upper and lower flanges and a connecting web, castings respectively secured to said channels, each of said castings having a base portion riveted to the lower flange of the channel member to which it is secured and an upper flange secured to the upper flange of said adjacent member, rear draft gear stops respectively secured to the forward ends of said channel members, and reinforcing ribs welded to the inner face of each of said draft gear stops and to the adjacent channel member, said reinforcing ribs being partially cut away above the riveted connections between the said members and said castings, said channel members being respectively adapted to be secured to said center sills.
